Specification for Design.

Patented Jan. 17, 1922.

Application filed January 29, 1921. Serial No. 441,057. Term of patent 3½ years.

To all whom it may concern:

Be it known that I, ALBERT A. HARRIS, a citizen of the United States of America, residing at Springfield, in the county of Hampden and Commonwealth of Massachusetts, have invented a new, original, and ornamental Design for a Holder for Crochet Thread, of which the following is a specification, reference being had to the accompanying drawing, forming a part thereof.

The figure is a side elevational view, showing my new design for a holder for crochet thread.

I claim:

The ornamental design for a holder for crochet thread, as shown.

ALBERT A. HARRIS.
